UNITED STATES PATENT OFFICE.

JOHN H. DALE, OF PHILADELPHIA, PENNSYLVANIA, ASSIGNOR OF ONE-HALF TO EDWARD D. DOUGHERTY, OF SAME PLACE.

GRIP-CARRIAGE FOR CABLE RAILROADS.

SPECIFICATION forming part of Letters Patent No. 364,490, dated June 7, 1887.

Application filed December 9, 1886. Serial No. 221,108. (No model.)

To all whom it may concern:

Be it known that I, JOHN H. DALE, of Philadelphia, in the county of Philadelphia and State of Pennsylvania, have invented certain new and useful Improvements in Grip-Carriages for Cable Railways; and I do hereby declare the following to be a full, clear, and exact description of the invention, such as will enable others skilled in the art to which it appertains to make and use the same.

My invention relates to an improvement in grip-carriages for cable railways.

The object of my present invention is to construct a grip-carriage that will obviate the shock incident to the sudden closure of the grip upon a moving cable, and permit such a closure to prevent slip and consequent wear of the cable, starting the car with a gradual increase of motion until the maximum speed of the cable is effectively transmitted to the attached car.

A further object is to provide a grip-carriage that will allow a grip mechanism to be rigidly and suddenly clamped to a running cable without shock or jar, and that will work with equal certainty when the car is run in either direction.

A further object is to construct a grip-carriage that will permit the sudden closure of the grip-jaw without shock, and that will afford yielding compensation for side sway of the car on curves, and thus accommodate the lateral vibration necessary to run an attached car on a curve and conform thereto without binding or strain of the connected and operating parts of the mechanism.

A further object is to furnish a grip-carriage that will afford the advantages hereinbefore enumerated, and that is of a simple, strong, and reliable character, that will permit ready access to its wearing parts for repair.

A further object is to construct a grip-carriage that will permit vertical adjustment of the supported grip-body to align it with a cable, and thus permit the picking up of the cable by the mechanism of the grip apparatus.

With these objects in view my invention consists in certain features of construction and combinations of parts, as will be hereinafter described, and pointed out in the claims.

In the drawings making a part of this speci-

fication, Figure 1 is a side elevation of the grip-carriage. Fig. 2 is a plan view of the device. Fig. 3 is a cross-section of the carriage on the line *x x*, Fig. 1. Fig. 4 is a view of the toggle-gear used to elevate and lower the grip-carriage. Fig. 5 is a cross-section of the carriage, showing a modified form of its bearing-flanges.

In the drawings, *R* represents string-pieces, preferably of timber, that are secured together by the cross-pieces *R'*, these together constituting a rectangular frame that is supported by pedestals and journal-boxes to fit the axle-journals upon which this frame is supported. Upon the inner sides of the frame-pieces *R*, that face each other, the journal-brackets *J* are secured, any suitable number being employed. The journals *g'* of the brackets *J* are made to support the bearing-wheels *J*².

A rectangular frame, *F*, of metal or other suitable material, is constructed, having its sides channeled to form flanges 1 2 3 4. The frame *F* is supported upon the wheels *J*² by the adjustment of its top flanges, 1 2, to bear on the wheel-faces, as shown in Fig. 3. At a point central between the wheel-brackets on each side piece, *R*, semi-elliptic plate-springs *W*, of proper size, are secured, preferably by a bolt, *b*, inserted through a central perforation made in each spring-leaf. These springs are slotted at their free ends a sufficient distance lengthwise to permit these bifurcated ends to be made to engage the rear faces of the wheels *J*² and press them outward upon their journals, washers *w* being introduced between the spring ends and the inner faces of the wheel-hubs to form an anti-friction surface.

The wheels *J*² are normally held by the springs *W* in running contact with the collars *u*, (see Fig. 2,) that are formed on the outer ends of the journals *g'*, these journals being made of sufficient length to allow a proper rearward movement thereon of the wheels *J*² when the lateral sway of the grip-carriage causes this movement and consequent compression of the springs *W*.

A modified form of the bearing-flanges on the grip-carriage is shown in Fig. 5. In this modification the flanges are L-shaped, and are secured to the sides of the carriage to form a

projecting bearing-face on each side to support the carriage on its wheels.

At each end of the rectangular frame F the vertically depending guide-bars G are fixed at 5 the center of these ends of the frame.

Below the frame F the horizontal arms B are placed in proper connection with the guides G. These arms B are attached at right angles to the grip-body A, and are intended 10 to hold this body in an upright position in relation to its sustaining-frame F thereon.

Upon the inner faces of the frame F the upper ends of the toggle-levers M are pivoted, the lower limbs, M', of these toggle-levers being 15 swing-connected to the inner faces of the horizontal arms B. Two longitudinal bars, N, are pivoted to the joined levers M M' in a manner to permit the oscillation of these levers by an endwise motion of the bars N N. (See 20 Fig. 2.)

A reversing-lever, O, in connection with a quadrant, P, constructed in the best approved form for such a device, is pivoted to the end of the bar N', to afford a means of vertical secured 25 adjustment of the grip-body A at any point within the range of the appliance.

At a point to the rear of the quadrant-stand P upon the frame-timbers R the cylindrical chamber S is mounted. This chamber is divided 30 by a partition, S', into two compartments. In the lower portion of the cylinder the plunger-head K is introduced, suitable packing being provided at its periphery to form a tight joint with the bore of the chamber. 35

To the lower end of the head K a plunger-rod, U, is pivoted. The lower end of this rod U is pivoted to the two-throw bell-crank I, that is placed on a stud, I'. The lower limb, 40 I', of the bell-crank I is pivotally secured to a connecting-bar, H, the opposite end of this bar being slotted of a length equal to the vertical travel of the plunger-head K. The slotted end of the connecting-bar H is slidingly connected 45 to a projecting stud that is secured to the lower side of the arms B at the point C. Upon the upper limb, J³, of the bell-crank I the connecting-bolt k is pivoted onto the fulcrum-bolt that secures the connecting-bar H' to this 50 limb J³. A spring, I⁴, is secured to the other end of the bolt k. This spring is designed to afford a means for the quick return of the plunger K to its normal position of depressed adjustment.

55 The transverse dividing-partition S' is perforated with two apertures of proper diameter. The aperture K³ has a valve-seat formed on its lower edge, and a valve that is spring-supported in contact with this seat is made to fit 60 the same with a tight joint.

The aperture K⁴ has a valve-seat made upon the top surface of the wall S' around the edge of this perforation, and has a valve, K⁵, fitted to it that is adapted to bear downward upon 65 this seat. A spring-attached connection, o, made between this valve and the screw and hand wheel L', permits a graduated adjustment

of the valve K⁵ to restrain the escape of oil or other liquid from the lower chamber, K', into the upper compartment. 70

The upper compartment of cylinder S has a sufficient amount of glycerine or other non-congealing liquid introduced therein to fill the vacant space in the lower chamber that represents the reciprocal travel of the plunger-head K. 75

In operation the normal position of the gripping-jaws of the cable-grip is above the horizontal plane of the running cable, and in order to depress the body A of the grip apparatus and permit its pick-up device to operate upon the cable the supporting-arms B are lowered by an adjustment of the lever O in regard to the rack or quadrant P, and secured in such adjusted position by the engagement of 80 the locking-toe e in the notches of the quadrant. 85

When the cable has been gripped by the clamping-jaws of the grip apparatus, of which A is the vertical body, the sudden progressive motion communicated to the grip-carriage F will cause it to move upon the supporting-wheels J² in the direction of cable travel, the connecting-bar H will receive and communicate motion to the bell-crank I, which will 90 cause an elevation of the plunger K in its cylinder, and the compressed liquid in the lower chamber will be forced by the impact of the plunger-head through the orifice K⁴. 95

The valve K⁵ being properly adjusted to effect a graduated escape of the liquid into the upper chamber, L³, the average speed of the cable being known, a spring compression is made upon the valve K⁵ to regulate the degree of resistance necessary, and thus afford an adequate 100 "cushion" to neutralize the shock or jar incident to the quick clamping action of the grip-jaws when a sudden attachment of these jaws is made to the running cable. 105

The position of relative parts, as just described, is maintained while the grip apparatus is in closed adjustment with the moving cable. When the car is stopped by a release of the cable, the spring I⁴, by its retractile force, causes the plunger-head K to descend in 110 the lower chamber, and by reason of the vacuum induced the liquid in the upper chamber will be drawn through the orifice K³ into the lower chamber, thus restoring all the parts to a normal position, as the length of the connecting-rod H is so relatively proportioned to the throw of the crank I that the rearward vibration of the lower limb, I', of this bell-crank I will restore the grip-carriage F to its central 115 position with regard to its carrying-wheels J². 120

When a car is to be run in an opposite direction, the cable-draft on the grip-body will be reversed, and the lever H' will pull the top end of the bell-crank and cause the plunger-head K to ascend in the cylinder. The operation of cushioning the jar of a sudden grip motion will be the same as when the car was run forward instead of the reversed movement just explained. 125

When the car to which this device is attached is running on a curve, the sway or side motion of the car-body will be compensated for by the provision of the semi-elliptic 5 springs W, as these will yield to the weight thrown on their ends by the impinge of the flanges of the wheels J², the springs being made of a proper length and strength to allow this lateral motion and cause the grip-carriage 10 F to assume a normal position when the strain is removed from these springs.

Slight changes may be made in the constructive details of this device and their arrangement somewhat altered without a departure 15 from the spirit of my invention. I therefore do not wish to restrict myself to the exact forms shown; but,

Having fully described my invention, what I claim as new, and desire to secure by Letters 20 Patent, is—

1. The combination, with a grip-carriage supported on wheels and adapted to move longitudinally, of a vertically-movable grip-body mounted on said carriage, substantially 25 as set forth.

2. The combination, with a flanged frame and two depending guides, of a grip-body mounted on said guides.

3. The combination, with a flanged frame 30 mounted on wheels secured to a car-frame, of springs adapted to bear against the rear faces of the wheel-hubs, substantially as set forth.

4. The combination, with a flanged frame, wheels that support the frame, and springs to 35 act on the hubs of the wheels, of two guides on the frame and a grip-body slidingly supported on these guides, substantially as set forth.

5. The combination, with a grip-carriage 40 supported on wheels and adapted to move longitudinally, and a vertically-movable grip-

ping device secured to said carriage, of a liquid cushioning device connected with said movable frame, substantially as set forth.

6. The combination, with a flanged frame, 45 its supporting-wheels, springs to bear on these wheels, and grip-body, of toggle mechanism to raise or lower the grip-body, substantially as set forth.

7. The combination, with a flanged frame, 50 its supporting-wheels, springs that bear on these wheels, and a suspended grip-body, of toggle-levers and reversing-gear to raise, lower, and secure in proper position the suspended grip-body, substantially as set forth. 55

8. The combination, with a flanged and wheel-supported grip-carriage and a suspended grip-body, of a hydraulic chamber having two compartments and actuating mechanism that causes the expulsion of liquid from one 60 chamber to the other, substantially as set forth.

9. The combination, with the timbers of a car and a flanged rectangular frame that has rolling support, a suspended grip-body that has vertical guides, toggle-gear to give up-and-down motion to the movable frame, and a yielding lateral support for the bearing-wheels of the flanged frame, of a cylindrical double-compartment hydraulic chamber, two valves, a 65 pressure-graduator for one of the valves, a plunger-head for the cylinder, a three-limbed bell-crank, two connecting-rods for this bell-crank, and a spring-retractor for the plunger-head, substantially as set forth. 70

In testimony whereof I have signed this 75 specification in the presence of two subscribing witnesses.

JOHN H. DALE.
